UNITED STATES PATENT OFFICE.

FREDERICK W. BANTZ, OF DALLAS, TEXAS, ASSIGNOR TO W. C. PADGITT
AND J. D. PADGITT, OF SAME PLACE.

DESIGN FOR A STIRRUP.

SPECIFICATION forming part of Design No. 29,415, dated September 27, 1898.

Application filed August 31, 1898. Serial No. 689,957. Term of patent 14 years.

To all whom it may concern:

Be it known that I, FREDERICK W. BANTZ, a citizen of the United States, residing at Dallas, in the county of Dallas and State of Texas, have invented and produced a new and original Design for a Stirrup, of which the following is a specification.

This invention relates to a new and original design for a stirrup; and it has for its object to provide a design of this character which shall be both useful and ornamental.

The leading feature of the design resides in the stirrup-body of an approximate **U** shape and provided with upright side arms having their lower ends deflected to one side in the same direction and a horizontal flat foot-plate connecting the lower deflected ends of said arms and disposed in a vertical plane at one side of the vertical plane of the latter.

While the essential feature of the design resides in the deflection of the lower ends of the side arms and the disposition of the flat foot-plate at one side of the vertical plane of these arms, the design involves a number of minor features, which may be enumerated as follows: the upright side arms being upwardly convergent and sigmoidally curved, with their lower deflected ends somewhat widened and disposed at an obtuse angle to the vertical plane of the greater length of the arms, said lower deflected ends being also curved inwardly into the end portions of the flat foot-plate. Other minor features of the design are the stirrup-body, having an exterior rounded bead extending continuously around the edges of its side arms and foot-plate, a cylindrical cross-bar connecting the side arms near their upper terminals and provided with vertically-alined elliptic slots in

the upper and lower sides thereof, transverse slots or openings formed in the terminals of the side arms, and elongated elliptical slots or openings formed in the side arms and also in the foot-plate of the body, said elongated elliptical slots having sigmoidally-curved edges meeting in an angle at points intermediate the ends thereof.

In the drawings, Figure 1 is a perspective view of a stirrup embodying the herein-de-

scribed design. Fig. 2 is a plan view thereof. Fig. 3 is an elevation. Fig. 4 is a vertical sectional view on the line 4-4 of Fig. 3.

Referring to the accompanying drawings, the numeral 1 designates the stirrup-body, which is of an approximate **U** shape and is provided with upwardly-convergent sigmoidally-curved side arms 2, having their lower ends widened, as at 3, and deflected to one side at an obtuse angle to the vertical plane of the greater length of the side arms. The widened deflected lower ends 3 of the side arms 2 are curved inwardly into the end portions of a horizontally-arranged flat foot-plate 4, which foot-plate by reason of the deflection of the lower ends of the upright side arms is disposed in a plane at one side of the vertical plane of said arms.

The body 1 is provided with an exterior rounded bead 5, extending continuously around the edges of the upright arms and foot-plate thereof, and said upright arms of the body are connected near their upper terminals by a transverse cylindrical cross-bar 6, provided with vertically-alined elliptic slots 7 in the upper and lower sides thereof, and the terminals of the upright side arms above the cross-bar have formed therein transversely-arranged slots or openings 8.

An additional feature of the design is the elongated elliptical slots or openings 9. One of the slots or openings is formed in each side arm 2 and in the foot-plate 4, and said slots are disposed longitudinally of the members of the stirrup-body. The said elongated elliptical slots or openings 9 are provided with sigmoidally-curved edges 10, which meet in an angle at points intermediate to the ends of the slots, as indicated at 11.

What I claim is—

The design for a stirrup herein shown and described.

In testimony that I claim the foregoing as my own I have hereto affixed my signature in the presence of two witnesses.

FREDERICK W. BANTZ.
